US0D1015490S

(12) **United States Design Patent** (10) **Patent No.:** **US D1,015,490 S**
(45) **Date of Patent:** **** Feb. 20, 2024**

(54) **VALVE**

(71) Applicant: **ASAHI YUKIZAI CORPORATION**,
Nobeoka (JP)

(72) Inventor: **Yukinobu Sato**, Nobeoka (JP)

(73) Assignee: **ASAHI YUKIZAI CORPORATION**,
Nobeoka (JP)

(**) Term: **15 Years**

(21) Appl. No.: **29/789,444**

(22) Filed: **Sep. 23, 2021**

(30) **Foreign Application Priority Data**

Mar. 24, 2021 (JP) ..... 2021-006151 D

(51) **LOC (14) Cl.** **23-01**

(52) **U.S. Cl.**

USPC **D23/245**

(58) **Field of Classification Search**

USPC D23/233, 235, 245

CPC Y10T 74/2084; Y10T 74/20474; Y10T

74/20; Y10T 74/20834

(57) **CLAIM**

The ornamental design for a valve, as shown and described.

DESCRIPTION

FIG. 1 is a perspective view of a valve showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

The broken lines depict portions of the valve that form no part of the claimed design.

1 Claim, 5 Drawing Sheets
